(57) **CLAIM**

The ornamental design for a lid for a container, as shown and described.

DESCRIPTION

FIG. 1 is a top (plan) view of a container lid embodying the new design;

FIG. 2 is a front elevation of the same container lid;

FIG. 3 is a bottom view of the same container lid;

FIG. 4 is a right side elevation of the same container lid looking from right to left in FIG. 1;

FIG. 5 is a cross-sectional view taken along line A—A of FIG. 1; and,

FIG. 6 is a cross-sectional view taken along line B—B of FIG. 1.

The left side view (not shown) is a mirror image of the right side view shown in FIG. 4.

The rear view is a mirror image of the front view shown in FIG. 2.
